UNITED STATES PATENT OFFICE.

JOHN L. McATREE, OF BROOKLYN, NEW YORK, ASSIGNOR TO SCOVILL MANUFACTURING COMPANY, OF WATERBURY, CONNECTICUT, A CORPORATION OF CONNECTICUT.

VANITY BOX AND COMPACT THEREFOR.

Application filed March 17, 1928. Serial No. 262,534.

This invention relates to certain improvements in the small boxes or cases now commonly known as vanity cases.

These cases are usually made of light metal and capacitated to hold toilet articles such as powder or rouge compacts, the boxes being made to hold either one such toilet article or two, the former being known as a single case and the latter as a double case. In merchandising this type of case, the compacts or other toilet articles are sold under a variety of trade names and the cases are usually decorated either by etching, enamelling or the like, or by suitable pasters selected to the case identifying the particular kind of compact or rouge sold with the case, or identifying the maker. Where a dealer carries in stock a number of different brands, he requires a box or case for each brand. It frequently occurs that one brand will sell faster than another with the consequence that the dealer will be out of a particular brand and will be stocked up with a number of boxes containing other brands.

It is the special object of the present invention to provide a vanity case and a compact therefor in which the vanity case is provided with a cut-out and the compact is decorated with any desired indicia indicative of its character or maker, such compact being removably held in the box and exposed through the cut-out.

A further object of the invention is to provide an improved construction whereby the compacts will be readily and quickly placed in the boxes and so that where a dealer desires he need carry but one type of box and can change the compact as necessary or desirable.

A further object of the invention is to produce a case of this character which shall be of neat and attractive appearance and in which the parts are few, so that the case can be cheaply made and assembled.

With these and other objects not specifically referred to in view, the invention consists in certain novel parts, arrangements and combinations which will be described in connection with the accompanying drawings and the novel features pointed out in the claims hereunto annexed.

Referring now to these drawings:

Figure 1 is a front edge view of the improved case and compact, the box being shown closed;

Figure 2 is a face view of the box of Figure 1, the box being shown open;

Figure 3 is a face view of the box and

Figure 4 is a sectional view on an enlarged scale, the section being taken on line 4-4 of Figure 2.

Referring now to these drawings, the box selected to illustrate the invention is what is known as a double box, that is, a box having a body and a cover pivotally associated therewith and capacitated to hold two toilet articles such as compacts. It will be understood, however, that the box shown is merely illustrative of the invention and that the invention, as to its broader features, may and will be used in boxes of widely varying form.

Referring now to the specific case shown, such case includes a box 1, and a cover 2, these parts being formed with side walls 3 meeting in the thin edge as indicated at 4. In accordance with the invention, one or both members of the case are formed with a central opening indicated at 5 surrounded by a marginal flange indicated at 6, the inner edge of this flange being preferably slightly beveled as indicated at 7. The particular box shown is provided with one of these cut-outs, the cut-out being shown in the cover, but it will be understood that each member of the case may be thus formed.

Secured in the case and supported by the flange 6 is a toilet article shown as a compact 8 carried on the usual metal base 9. This compact is supported in the box so that its bottom or base is visible through the cut-out, and in accordance with the invention, the base is provided with any desired decoration. This decoration may be applied to the base in any suitable manner, but in the particular construction shown, is formed on a label of paper indicated at 10, this paper being secured as by pasting to the base. It will be understood, of course, that if desired, the base itself may be decorated as by etching or in any other suitable manner.

It will be seen that with this construction, the compact forms in itself the cover or bottom of the case and the same case may be employed for compacts having various distinguishing indicia.

The compacts are supported in the case so as to be readily removed. While this may be

effected in various ways, in the particular construction shown, the two parts of the box are pivotally associated on a hinge 11, which is formed on two bezel members 13, 14, which are snapped past an inturned rim 15 on the walls of the case, the parts being thus associated together. These bezels are provided with fixed nibs 16 and a movable nib shown in the form of a spring wire 17 having an inturned end 18 projecting inward through the wall of the bezel. When it is desired to remove the compact, by moving the spring inwardly the bezel is freed and may be removed from the case and another compact 15 may be substituted therefor. If desired, a spring catch 19 may be provided for securing the parts together.

The case may be of various shapes, that shown being a preferred one as it forms a small thin case of attractive appearance. Where the case members are convex as shown, the compact will be similarly shaped and will project through the cut-out in the case. It will be understood that cases and 25 compacts of other shapes may be employed within the invention.

It will be seen that with the construction shown and described a dealer may keep but one type of box in stock and can fill this 30 box with compacts having the desired indicia and this can be done in a quick and

expeditious way. While the invention has been shown and described in its preferred form, it will be understood that various changes may be made in the shape and form of the case and compact and in the means for holding the compacts in position in the case without departing from the invention as defined in the appended claims.

What I claim is:

1. In a vanity case, the combination of a body and a cover, one of these parts being provided with an opening surrounded by an annular flange, and a compact holding base having an exterior provided with identification means and removably retained in the case so that it forms a part of the case and the identifying means is exposed through the opening.

2. In a vanity case, the combination of a body and a cover, one of these parts being provided with an opening surrounded by an annular flange, a compact holding base having a label or the like secured to the exterior face thereof and means for securing the base in the case so that it forms one wall thereof and the label is visible through the opening.

In testimony whereof, I have hereunto set my hand:

JOHN L. McATREE.
